UNITED STATES PATENT OFFICE.

ALBERT EDWARD DAY'S BAY ROD, OF WELLINGTON, NEW ZEALAND.

GAME.

1,421,570.

Specification of Letters Patent.

Patented July 4, 1922.

Application filed January 22, 1920, Serial No. 353,297. Renewed May 23, 1922. Serial No. 563,123.

To all whom it may concern:

Be it known that I, ALBERT EDWARD DAY'S BAY ROD, a citizen of the Dominion of New Zealand, and residing at Day's Bay Pavilion, Day's Bay, Wellington, in the Provincial District of Wellington, a subject of the King of Great Britain and Ireland, have invented certain new and useful Improvements in An Improved Game, of which the following is a specification.

This invention relates to games played on boards with movable pieces, and provides improved means whereby a game of mimic warfare can be played on a specially prepared board with the aid of movable pieces.

According to the invention the board is made to correspond on a reduced scale with a section of "No Man's Land," or with a section of that portion of a battle field located between the front trenches of opposing armies engaged in warfare.

Besides the usual trenches and parapets the area between the trenches is divided into rows of squares parallel with the trenches and also into rows of squares parallel with each other and running from one trench to the other, at right angles to the latter.

The rows of squares parallel with the trenches are marked at each end with equal values, the latter commencing with the row adjacent each trench and decreasing in value towards and ceasing at the rows on either side of the centre of the board.

There are the same number of rows of squares parallel with the trenches as there are rows of squares at right angles to the latter.

The game is played by two persons each of whom is provided with the same number of consecutively numbered movable pieces as there are rows of squares at right angles to the trenches.

The invention will be further described with reference to the accompanying drawing:—

Figure 1 being a plan view of a board showing the pieces in the trenches and

Figure 2 a cross sectional elevation of a board, while

Figure 3 is a perspective view of a movable piece.

In the drawing the board 1 which is made to correspond with a section of No Man's

Land, has thereon at opposite sides, parallel trenches 2, and parapets 3, with a division 4 parallel with and midway between said trenches 2.

The space between the trenches 2 consists of a number of rows 5 of squares, parallel with said trenches, while parallel rows 6 of squares at right angles to said rows 5 extend from trench to trench.

The rows 6 are termed "lines of fire" and the rows 5 have scoring numerals of equal value at each end, the highest of said numerals being located at each end of the rows 5 adjacent the trenches 2. The numerals at the ends of the rows 5 decrease towards the division 4 so that the rows 5 on either side of said division 4 are of the same value.

There are the same number of rows 5 as there are rows 6, so that the areas between the trenches 2 is approximately square, with side columns 7 containing the scoring numerals opposite the rows 5.

Each of the two players has the same number of consecutively numbered pieces 12 as there are rows of lines of fire 6 the pieces of one player being of a different color to the pieces of his or her opponent. Each player 80 has a piece or man 12 numbered to correspond with one of his opponent's pieces or men and arranges his or her pieces 12 in any order in his or her trench 2 or behind the parapet or top 3 thereof.

To begin, a player may move any one of his pieces over the parapet or top 3 into any square in the first row 5 in front of his trench 2 providing the opponent has not already got his corresponding piece in the same line of fire 6. A player is not bound to move any of his pieces into the square directly in front of same.

The players play alternately and each piece or man may be advanced, moved sideways, or backwards one square at a time, but must not be placed again in the trench from which it was taken.

No two pieces can occupy the same square, nor may any piece be passed over another 100 piece, but must be worked round it.

Each square has a scoring value equal to the numerals marked at the end of the rows 5, in which it is located.

A player must not move a piece into a 105 line of fire 6 in which the correspondingly

numbered piece of his opponent is located, as two similarly numbered pieces in the same line of fire 6 are "out of action," except when one piece is shielded in a trench 5 2 or behind a parapet or top 3.

Differently numbered pieces in the same line of fire do not effect one another.

To put a piece "out of action" a piece 12 must be moved into a line of fire 6, in which 10 the opponent's piece of the same number is situated. Intermediate pieces are not effected nor do they act as shields.

The player who in this way puts a piece 15 of his opponent's out of action, adds to his score the value of the row 5 in which the opponent's piece was located when put out of action. Both men are then removed from the board.

Two correspondingly numbered men side 20 by side remain so until one is forced to move.

When a player manoevers a piece across the board into his opponent's trench he adds 100 to his score plus the value of the row 5 25 in which the opponent's correspondingly numbered piece is located. If the latter piece has not been moved from its home trench then the aforesaid player adds 200 to his score.

30 A piece in a trench is not in a fixed position and can be moved aside to allow another piece to enter.

If a piece is prevented from entering a trench by one or more of the opponent's 35 pieces in front of the trench, a player should not waste his moves by working his piece around the obstructing pieces, but should endeavor to put one or more of the obstructing pieces "out of action."

40 When a player's piece has crossed the board into opponent's trench, or puts the opponent's corresponding man out of action, the successful player in removing the two pieces places them on the right hand side of 45 the board against the numerals, represent the addition to his score.

What I do claim and desire to secure by Letters Patent of the United States is:—

1. Apparatus for playing a game, consisting of a board with parallel trenches and 50 parapets at opposite sides; a division midway of the trenches and parallel therewith; rows of squares parallel with each other and at right angles to the trenches and extending 55 from one of the latter to the other; scoring numerals at the ends of the rows of squares parallel with the trenches, increasing in value from the trenches towards the centre of the board, and consecutively numbered 60 men for moving on said board.

2. Apparatus for playing a game, consisting of a board with parallel trenches at opposite sides, rows of squares parallel with each other and at right angles to the trenches and extending from one of the latter to the 65 other; scoring numerals at the ends of the rows of squares parallel with the trenches, increasing in value from the trenches towards the center of the board, and consecutively numbered 70 men for moving on said board.

3. Apparatus for playing a game, consisting of a board with parallel trenches and parapets at opposite ends, a depressed portion extending across the center of the board 75 between the projections to form a division, rows of squares between the projections and on either side of said depression, parallel with each other, and at right angles to trenches and extending from one of the latter to the other; scoring numerals at the 80 ends of the rows of squares parallel with the trenches, increasing in value from the trenches towards the center of the board, and consecutively numbered 85 men for moving on said board.

In testimony whereof I affix my signature in the presence of two witnesses.

ALBERT EDWARD DAY'S BAY ROD.
